OUTLET BOX SUPPORT

Lester L. Elstad, Minneapolis, Minn.

Application September 26, 1949, Serial No. 117,863

4 Claims. (Cl. 248—27)

1

This invention relates to a support for electrical outlet boxes and the like.

While it is contemplated that the device will be used in other than ceiling installations, it is described herein as used in conjunction with a ceiling construction.

An object of the invention is to provide an outlet box support which is particularly adaptable for use in installing electrical fixtures in houses or other buildings which are already constructed, and wherein effective means is provided for properly anchoring the outlet box support.

Another object of the invention is to provide an outlet box support adapted to be placed between a pair of spaced panels such as the lath of a plaster ceiling or the upper side of any conventional ceiling panel, and the underside of flooring which is spaced above the ceiling, the said support being used to anchor the outlet box either permanently or until it can be screwed or otherwise attached in place.

A further object of the invention is to provide means for tightly and securely mounting an outlet box support between two panels, the said means including mechanism whereby the device can be readily adjusted or slightly re-arranged to accommodate itself to building constructions wherein the space between the two panels varies considerably.

Still another object of the invention is to provide a device of the general character described above which can be readily adapted for use in supporting a conventional outlet box or a shallower pan which may be used.

The above and other objects and advantages of the invention will more fully appear from the following description made in connection with the accompanying drawings, wherein like reference characters refer to the same parts throughout the views, and, in which:

Fig. 1 is a fragmentary sectional view through part of a ceiling and superimposed floor illustrating the adaptation of an embodiment of my invention thereto.

Fig. 2 is a similar view showing the device arranged for supporting a ceiling pan.

Fig. 3 is a sectional view showing the device lengthened vertically so that it will function in a structure where the space between the ceiling and the floor thereabove is considerably greater than in Figs. 1 and 2.

Fig. 4 is an enlarged fragmentary sectional view taken approximately on the line 4—4 of Fig. 2.

Fig. 5 is a perspective view of the member for bridging the ceiling opening.

Fig. 6 is an enlarged fragmentary sectional view taken approximately on the line 6—6 of Fig. 3.

2

Fig. 7 is a fragmentary sectional view through part of a ceiling illustrating the adaptation of another embodiment of my invention thereto.

Fig. 8 is a perspective view of the member for bridging the ceiling opening used in the embodiment of my invention shown in Fig. 7, and

Fig. 9 is a vertical sectional view of the bridging member shown in Fig. 8, taken transversely through the middle aperture therein.

10 In Fig. 1 there is shown a portion of a ceiling panel indicated generally at 6 and made up of a plurality of conventional laths 7 and a plaster coating 8. Spaced above the ceiling panel is a floor 9 which, of course, is the floor of the room 15 above the ceiling 6. The ceiling panel has an opening 10 formed therethrough.

Extending across the opening 10 is a bridging member 11 having flat ends 12 which preferably should span approximately two of the laths 7.

20 The bridging member 11 has a raised central portion 13, which is somewhat higher than the flat ends 12. The central portion 13 is provided with a central aperture 14 and the medial edge portions are turned upwardly as at 15 to provide 25 reinforcement for the strap material which forms the center of the bridge 11.

Extending into the opening 14 is a threaded spud 16 having an upper flange 17, which rests upon that portion of the bridging member 11

30 which defines the aperture 14. This spud is shown in detail in Fig. 4. It has an internally threaded bore 18, and a threaded rod or compression member 19 is mounted therein. This rod preferably has a pointed upper end 19a. A 35 conventional electrical outlet box 20 with an upper central aperture is slipped on the lower end of the spud 16, as shown in Fig. 1, and a retaining nut 21 is screwed on the spud to secure the outlet box between said spud and the underside of the raised central portion 13 of the bridge 11. It will be seen that the lower end of the threaded rod 19 has a kerf 19b formed therein.

The parts can be placed in approximate position as indicated in Fig. 1 prior to placing of the 40 outlet box 20 thereon. When the bridging member and rod 19 are originally inserted, the rod 19 is not extended upwardly as far as shown in Fig. 1, but is turned up into engagement with the underside of the floor 9 after the parts have been

45 positioned so that the bridging member 11 will be pressed firmly down on the tops of laths which lie on either side of the ceiling panel opening 10.

Figs. 2 and 4 show a modification of the structure shown in Fig. 1. An adapter 22 is provided 50 with an internally threaded portion 23 and an externally threaded portion 24, the two sets of threads being of the same pitch and diameter. The adapter 22 also has a bore 24a which extends through the externally threaded end portion 24,

so that the threaded rod 19 can extend therethrough. A ceiling pan 25 with an upper central aperture 26 is slipped on the lower end 24 of the adapter 22 and a retaining nut 27, which is the same as the nut 21 in Fig. 1, is used to hold the pan 25 in position between said nut and the shoulder located at the upper portion of the threads 24 on the adapter. Since the ceiling pan 25 is usually shallower than an outlet box such as the box 20 of Fig. 1, the adapter 22 is used to lower the point of mounting of said pan 25.

In Figs. 3 and 6 the adapter 22 is shown threaded on the spud 16 with the shoulder of the adapter resting upon the upper side of the bridging member 11. An outlet box 28 is slipped on the lower end of the adapter 22 and retained by a nut 29, similar to nuts 27 and 21 in Figs. 4 and 1, respectively. By placing the adapter 22 above the central bridge portion 13, the same rod 19 can be extended upwardly further where the ceiling and the overlying floor are spaced further apart.

An outlet box or ceiling pan mounting such as described is of particular advantage when wiring homes that have already been constructed. The provision of a bridging member and an extensible strut or compression member such as the rod 19 results in an extremely firm anchoring support for the outlet box. It does not require anchoring screws in the ceiling laths, a practice which is not advisable because the laths often split or they may be rotted. The flat ends or legs 12 of the bridging member 11 should be made long enough to contact at least two of the ceiling laths, as shown in the drawing so that a strong support will be provided.

Figs. 7, 8 and 9 show an additional embodiment of my invention which is simple, yet novel and very effective. It comprises a bridging member 30 somewhat similar to the member 11 in that it has a raised central portion 30a which is provided with a central aperture 31 and reinforcement flanges 30b. It differs, however, in that the aperture 31 is threaded, having a bore of equal pitch and diameter as the thread of the threaded portion 32 of the rod 33 which is mounted therein. The raised central portion 30a also has additional apertures 35 disposed between its ends and the central aperture 31 adapted for fastening the various sized conventional outlet boxes which are equipped with corresponding apertures for fastening said outlet box securely. The rod 33 has a longer unthreaded portion than the rod 19 and its overall length is accordingly considerably longer. The unthreaded portion of the rod 33 has break-joint notches 34 cut therein at spaced intervals. When in approximate position the rod 33 is screwed by means of a screw driver inserted in the kerf 33b upwardly until the top end of the rod 33a engages the underside of the floor 9 above the ceiling and presses the bridge member 30 firmly down on the tops of the laths which lie on either side of the ceiling panel opening 10. Then the outlet box 20 is slid over the lower end of the rod 33 and the retaining nut 36 is screwed onto the rod 33 below the outlet box 20 so as to hold it firmly and securely in place. Additional support and rigidity can be provided for the outlet box by inserting ordinary bolts through the additional apertures 35 and the corresponding apertures in the outlet box and fastening them tightly with nuts.

The big advantage of the embodiment of the invention shown in Fig. 7, 8, and 9 is its ready ad-

justability to spaces of different distances. The rod 33 is made of sufficient length so as to extend from the ceiling to the floor above it even in cases when these two members are separated by an unusually large distance. If the rod 33 proves to be too long for the space between the floor and ceiling below it, the user can easily break the rod 33 at one of the points where the break-point notches are located so as to make the rod 33 of the desired length. This structure obviates the need of the spud 16 and the adapter 22 shown in Fig. 2 and utilized in the other embodiment of my invention when the rod 19 was not long enough for the purposes at hand, and has the advantage of being considerably simpler and cheaper to manufacture while still efficiently accomplishing its purpose.

It will, of course, be understood that various changes may be made in the form, details, arrangement and proportions of the various parts without departing from the scope of my invention.

What I claim is:

1. In an outlet box support, a bridging member having an opening therethrough, a spud extending through said opening and having a portion supported on said bridging member, the lower portion of said spud being externally threaded and providing means for supporting an outlet box and a threaded rod threaded into said spud and extending upwardly thereabove and above said bridging member.
2. The structure in claim 1 and an extension adapter for said spud having one end internally threaded and the other end externally threaded, the diameters of said threaded ends being the same.
3. An outlet box support comprising a bridging member adapted to span a building panel opening, a threaded compression rod member extending through said bridging member and upwardly above to engage the surface of a panel spaced from said first mentioned panel, said threaded rod being shiftable longitudinally to extend the same relative to said bridging member and said rod including means for varying its length to easily adapt its length to said space, and at least one of said members being arranged to support an outlet box thereon.
4. An outlet box support adapted to be used between a pair of spaced panels, one of which has an outlet box opening therein within which an outlet box is adapted to be placed, said support comprising a bridging member adapted to bear against the inner side of the apertured panel and span the opening therein, a strut having screw threaded connection with said bridging member and extensible beyond the same to bear against the non-apertured panel, said strut having break joints therein at longitudinally spaced intervals whereby the effective length of the strut between the bridging member and the non-apertured panel can be readily varied by breaking the strut at one of the break points.

LESTER L. ELSTAD.
